UNITED STATES PATENT OFFICE.

GEORG STEINMETZ, OF CHARLOTTENBURG, NEAR BERLIN, GERMANY.

PAPER CLIP.

Application filed April 1, 1925, Serial No. 19,903, and in Germany March 2, 1925.

This invention relates to a paper clip for loosely filing or suspending sheets of paper, such as letters, drawings and the like, either singly or in bundles.

5 The invention has for its main object the provision of a paper clip which will securely hold bundles or packs of considerable size and thickness.

Another object of the invention is the provision of a paper clip of most simple and effective design by winding and bending the spring forming the clip repeatedly in different planes, so that the clamping strips of the clip, which engage the sheets to be held, 15 will hold same securely in any position without relaxation of the spring ends by means of which the pressure on the paper is applied.

A further object of the invention is to so 20 construct the clip that the applied spring pressure will act evenly all over the full length of the sheets to be held.

According to the invention the paper clip is designed so that the various members of 25 the clip and the suspension member co-operate efficiently to clamp the paper in place irrespective of whether thin or thick bundles of paper are secured thereon.

The clip, apart from the spring proper, 30 consists of a back or outer strip and an inner strip, of which the latter is formed so as to eliminate friction and so as to impart increased strength and security to the spring ends. Besides, the spring is connected to 35 the back of the clip at a neutral point, and its effective parts are thus able to move freely, while the spring ends always take that position which gives the greatest spring pressure upon the sheets to be held.

40 The accompanying drawing illustrates the invention by way of example.

Fig. 1 is a front elevation of the improved paper clip, while Fig. 2 is a part sectional side elevation thereof.

45 Figure 3 is a vertical sectional view of the same showing the situation of paper held in gripping position.

Figure 4 is a detail view showing the means for securing the spring *a* to the back 50 of the outer strip.

Figure 5 is a detail vertical sectional view of the same.

In this drawing *d* is the back or outer strip having a depending bent-over top edge 55 *c* enclosing the likewise depending top edge

portion *d*² of the inner strip *d*'. The sheets of paper to be held are clamped by means of the spring clip *a* which is fastened at its U-shaped neutral or dead position *b* to a T-shaped member *i* which member is secured by eyelets *h* or other suitable means to the depending edge *c* of the back *d*. The said spring clip, according to the drawing, is formed of one continuous length of spring wire to form the U-shaped central portion 60 and the oppositely extending arms, which arms are united to the U-shaped portion by coils *a'*, the ends being formed of spring coils *e* and also bent to form integral hooks or loops *f* and so that the suspension hooks 70 or loops of which are formed in the wire extend into the free ends *e* which are arranged between the inner strip *d*' and its folded or bent over edge portion *d*². Between the said free ends and the suspension 75 hooks the spring is set off to form a shoulder *h*. It is preferable to provide the inner strip *d*' at its depending top edge with a metallic ledge or other strengthening member *g* which also serves to eliminate or re- 80 duce the friction between these parts.

The invention evidently is not limited to the exact configuration shown in the drawing but may be modified to meet requirements within the scope of the following 85 claims.

What I claim is:—

1. A clip of the class described, comprising an outer strip and an inner strip, each provided with a bent over edge portion, that 90 of the inner strip being arranged in the bent over edge portion of the outer strip and a spring connected to said strips and arranged to exert its tension between the inner strip and its bent over edge and to also exert its 95 tension on the bent over portion of the outer strip to press the folded or bent over portions of said strips together to clamp paper therebetween.

2. A clip of the class described, comprising an outer strip and an inner strip, each provided with a bent over edge portion, that 100 of the inner strip being arranged in the bent over edge portion of the outer strip and a spring exerting its tension between the inner strip and its bent over edge and also exerting its tension on the bent over portion of the outer strip to press the folded or bent over portions of said strips together 105 to clamp paper therebetween, said spring 110

comprising a piece of spring wire attached to the bent over portion of the outer strip and having a spring coil bearing on the folded portion of the outer strip and a spring terminal bearing between the inner strip and its folded over edge to press the folded portions of said strips together.

3. A clip of the class described, comprising an outer strip and an inner strip, each 10 provided with a bent over edge portion, that of the inner strip being arranged in the bent over edge portion of the outer strip and a spring exerting its tension between the inner strip and its bent over edge and also exerting its tension on the bent over portion of the outer strip to press the folded or bent over portions of said strips together to clamp paper therebetween, said spring comprising a piece of spring wire attached to the bent 20 over portion of the outer strip and having a spring coil bearing on the folded portion of the outer strip and a spring terminal bearing between the inner strip and its folded over edge to press the folded portions of said strips together and being also bent to

form a hook wherewith to suspend the device.

4. A clip of the class described, comprising an outer strip and an inner strip, each 30 provided with a bent over edge portion, that of the inner strip being arranged in the bent over edge portion of the outer strip and a spring exerting its tension between the inner strip and its bent over edge and also exerting its tension on the bent over portion 35 of the outer strip to press the folded or bent over portions of said strips together to clamp paper therebetween, said spring comprising a spring wire bent to form a central portion and oppositely extending arms, said 40 central portion being secured to the folded over edge portion of the outer strip and said spring wire being formed with coils which bear on said folded over portion, being also bent to form hooks wherewith to suspend 45 the device and the free terminal portions which bear in the fold of the inner strip.

In witness whereof I affix my signature.

GEORG STEINMETZ.
